UNITED STATES PATENT OFFICE

WILLIAM K. MASON, OF CAMBRIDGE, MASSACHUSETTS, ASSIGNOR TO AMERICAN ELECTRICAL COMPANY, OF BOSTON, MASSACHUSETTS, A CORPORATION OF MASSACHUSETTS

COMBINATION LOCK SWITCH

Application filed September 18, 1929. Serial No. 393,357.

This invention relates to an electric switch which may be controlled after the manner of a combination lock by rotating a knob or the like through certain predetermined angles which may be indicated conveniently by a dial and index. According to the invention a normally open switch, suitably enclosed to prevent unauthorized access thereto, may be closed by correct manipulation of an exposed operating knob, but the correct combination of numbers on the dial must be known to the operator to enable him to close the switch. Among the various uses to which such a switch may be put, an illustrative use is found in connection with a burglar alarm installation in a building. Such an alarm system may include a closed switch associated with each window and door in such a way that if any one of the switches is opened by motion of a door or window, the alarm is actuated. When a building is left over night with such an alarm system in operative condition, it is desirable to provide entrance for authorized persons without setting off the alarm. To this end a shunt may be provided around the alarm switch attached to the entrance door so that when the shunt circuit is closed, the door switch may be opened without actuating the alarm. The shunt switch may be mounted at any convenient place within the building, preferably on or near the door itself. An operating spindle extends to the outside of the building and may carry a knob for actuation of the switch elements. The latter may be pushed around until each is individually touching a corresponding contact point, the shunt circuit being thereby closed. In order to accomplish this, however, the operator must know at what points the rotation of the knob must be reversed. There is no opportunity afforded to determine the correct combination by trial and error since if the circuit is not closed on the first attempt, the opening of the door starts the alarm.

For a more complete understanding of the invention, reference may be had to the description thereof which follows, and to the drawing, of which,—

50 Figure 1 is an elevation of the external as-

pect of a switch embodying the combination as installed.

Figure 2 is a section on the line 2—2 of Figure 1.

Figure 3 is a section on the line 3—3 of 55 Figure 2.

Figure 4 is a fragmentary perspective view of the working portions of the switch.

Figure 5 is a section on the line 5—5 of 60 Figure 3.

Figure 6 is a diagrammatic wiring plan of 65 a typical burglar alarm system illustrating one use to which the invention may be put.

Referring to the drawing, 10 represents a door or wall of a building on the inside of 70 which the switch may be mounted. The switch mechanism may for convenience and protection be enclosed in a suitable housing 11 having a cover plate 12. The switch mechanism itself comprises a circular plate or 75 disk which, for convenience, may be composed of a pair of disks 13, 14 secured together face to face. These disks may be centrally perforated as at 15 to receive a spindle 16 by which the switch is operated. Loosely mounted on the spindle 16 are a pair of arms 17, 18, these arms being independently revoluble around the spindle 16. Since the spindle 16 may conveniently be made of metal, a suitable sleeve 19 of insulating ma- 80 terial such as fiber, bakelite, or the like may be carried on the spindle, as shown in Figure 5. Over the sleeve 19 may be a metal sleeve 20 having end flanges 21 flush with the opposite ends of the sleeve 19. The metal sleeve 20 preferably fits within the perforation 15 so that in assembling the device, one of the flanges 21 is formed after the sleeve 20 has been threaded through the perforation 15. Between one of the flanges 21 and the adjacent face of the disks 13, 14 are mounted the arm 17 and a pair of washers 22, one on either side of the arm. The washers 22 are preferably of metal so that while the arm 17 is free to rotate about the sleeve 20, a good electrical contact between the arm 85 and the sleeve is maintained. In like manner the arm 18 is mounted on the sleeve 20 between a pair of metal washers 22 on the other side of the disks 13, 14. The arms 17 and 90

95 Figure 1 is an elevation of the external as- 100

18, as shown in Figure 5, are preferably bent outward away from the disks 13, 14 and are provided respectively with inturned portions 23, 24 which bear against the faces of the disks 5 13 and 14, respectively, so that as the arms 17 and 18 are swung around the axis of the spindle 16, their outer ends constantly rub against the faces of the adjacent disks. To this end the arms are preferably made of spring metal.

10 As shown in Figure 4, a metallic contact element 25 is set into the disk 13 so that its face is flush with the outer face of the disk. The element is in the path of the contacting portion 23 of the arm 17, so that when 15 the arm 17 is swung about the axis of the spindle the end 23 may come into contact with the element 25. As shown, the element may be extended as at 26 to the rim of the disk 13 where it may be conveniently connected to a suitable wire 27. A similar element 28 may be mounted in the disk 14 so as to be in the path of the contact portion 24 of the arm 18. This element may have an extension 29 projecting from the rim of the 25 disk and connected to a suitable wire 30. Thus if the wires 27 and 30 are connected into a circuit, there are normally two gaps in this circuit when the switch is open, one of these 30 gaps being between the arm 17 and the contact element 25, the second gap being between the arm 18 and the element 28. Since the arms 17 and 18 are constantly connected electrically through the sleeve 20, the circuit through the wires 27, 30 may be closed by causing the 35 arms 17 and 18 to contact simultaneously with the elements 25 and 28, respectively.

For the purpose of revolving the arms 17 and 18 independently around the axis of the spindle 16, I may provide a suitable member 40 31 projecting laterally from the spindle 16 and secured thereto. As shown, the member 31 may be in the form of a set screw threaded into a collar 32 which is mounted on the spindle 16. The set screw 31 may thus not 45 only have the function of adjustably securing the collar 32 to the spindle 16, but also projects from the spindle sufficiently to be in the path of a portion of the arm 18. Thus if the spindle is rotated, the set screw or abutment member 31 swings around with it and 50 eventually brings up against one side or the other of the arm 18. Continued movement in the same direction will result in a pushing of the arm 18 around the axis of the spindle. 55 If, now, the direction of rotation of the spindle be reversed, the member 31 swings away from the arm 18 and leaves the latter motionless. In addition to the set screw 31, I may also provide a second set screw or abutment member 33 which may be screw-threaded 60 into the collar 32 at a point diametrically opposite to the member 31, as shown in Figure 3 or at any other point desired. Thus when the member 31 is swung away from contact with the arm 18, the member 33 ap-

proaches the other side of the arm 18 and eventually engages it to swing it in the opposite direction. The member 33 may also be employed as an additional set screw to insure the firm engagement of the collar 32 on the 70 spindle 16.

The arm 17 may also be moved about the axis of the spindle in a similar manner. As shown, a single set screw 34 is provided, this screw being set in a collar 35 which is on the 75 spindle 16 and may be adjustably secured to the spindle by a set screw 34. A second set screw may be employed opposite the set screw 34 to assist in securing the collar 35 to the spindle 16, but if such a set screw be used it is preferred not to have it engage the arm 17. When the spindle is rotated, the abutment member 34 swings around until it engages a side of the arm 17, whereupon further rotation of the spindle in the same direction results in a swinging of the arm 17 about the axis of the spindle.

In order to insulate the arms 17 and 18 and their washers 22 completely from adjacent metallic parts, I may provide a pair of insulating washers 50 of fiber, bakelite, or similar insulating material to cooperate with the insulating sleeve 19 in preventing a possible short circuit between the arms 17, 18 through the collars 32, 35 and the spindle 16.

Since the working mechanism of the switch is normally hidden from view, and since the faces of the contact points 25 are flush with the faces of the disks 13 and 14, it is necessary for the operator to know just how far to turn the spindle 16 in order to move the arms 17 and 18 successively into contact with their respective contact points 25 and 28. The switch, as a whole, is intended to be mounted, as shown, on the inner side of a door or wall 10. The spindle 16 projects through the door or wall 10 and may be provided with a suitable bushing 36 to facilitate rotation. As shown in Figure 2, the bushing 36 may be mortised into the housing cover 12 on which the mechanism is mounted. This aligns the mechanism accurately with the hole through the door so that when the spindle 16 is thrust through the door to be connected to the switch mechanism in the course of installation it will be properly aligned with the hole, and will not bind therein. Mounted on the outer end portion of the spindle 16 is a finger knob 37 having a conical portion 38 which is divided by peripheral scale marks which may cooperate with an index mark on the door or on a suitable plate 39 secured to the door.

In operating the switch to close the circuit, the operator turns the knob 37 in a specified direction which depends upon the adjustment 125 of the collars 32 and 35. When the proper scale mark is opposite the index mark, this indicates that the abutment member 34 engaged the arm 17 and has swung that arm about the axis of the spindle until the contact 130

end 23 is resting on its contacting element 25. The knob 37 is now reversed leaving the arm 17 in contact with the element 25. This reverse rotation of the knob 37 results in an eventual engagement of the member 31 or 33 with the arm 18, this arm being thereupon revolved around the spindle until the dial indicates that the arm is in contact with its contact element 28. If the rotation of the knob 37 is stopped at this point, both the arms are simultaneously in contact with their respective contact elements so that the circuit is completed through the switch. Any motion of the knob which moves either or both of the arms from their contact elements opens the switch.

A typical use of a switch of this type is illustrated in Figure 6. Herein is shown an alarm circuit 40 having therein a suitable battery 41, or other equivalent source of electrical energy, a number of normally closed switches 42 which may be attached to windows or at other points in a building to open in case the window is tampered with, a similar switch 43 to be mounted on the door customarily used by the occupant of the building for access thereto, and an electromagnetic relay 44 which, as shown, may hold a switch 45 normally open but which allows the switch 45 to close when a circuit 40 is broken. Closing of the switch 45 results in the sounding of a suitable alarm 46 by means of a battery 47. It is desirable to provide for the occupant of the building means of access thereto without setting off the alarm 46. For this purpose a shunt circuit 48 may be provided about the switch 43 so that if the shunt circuit 48 is closed, the switch 43 may thereupon be opened without setting off an alarm. The shunt circuit 48 may thus comprise a pair of wires 27 and 30 connected to the switch mechanism hereinbefore described. The knob 37 being on the outside of the door or wall of the building is accessible and may be operated to close the switch, and thus to permit entry into the building without actuating the alarm. It is necessary, however, for the operator to know the correct dial numbers; otherwise the arms 17 and 18 are moved past the contact elements 25 and 28 instead of being allowed to rest thereon. The possibility of accidental closing of this switch by random operation of the knob is infinitesimal. In order to provide against successful operation of the switch by an expert, sensitive to the change of "feel" of the knob when the arm 17 or 18 passes from the surface of its insulating disk to the surface of its contact element, I may provide a number of dummy contact elements 49 having faces flush with the disk 13 or 14 in the same manner as the contact elements 25 and 28. One or two such dummy contact elements may be mounted in each disk or, for further security, a con-

siderable number of them may be mounted in a ring in each disk, as indicated in Figure 3.

By a simple change of wiring the switch shown may be used as a normally closed switch to be opened rather than a normally open switch to be closed. To this end a considerable number of contact elements may be set into each disk, successive elements being sufficiently close together to enable the contact end 23 or 24 to bridge the intervening space so that the arm is always in contact with at least one of the elements in its disk. If all the elements except one in each disk be electrically connected to the lead 26 or 29, the switch will remain closed until the arms 17 or 18 are in contact with the one contact element in each disk which is not connected to the respective leads. Thus in order to open the switch the correct dial combination must be known.

The invention is not limited to the particular embodiment herein illustrated and described but includes all such modifications and changes which fall within the scope of the appended claims.

I claim:

1. A device of the class described comprising a rotatable spindle, a pair of arms having electrical contact points and loosely mounted to revolve independently about said spindle, a pair of abutment members projecting laterally from said spindle and movable by rotation of the spindle into engagement with said arms respectively, whereby said arms may be independently moved by rotation of said spindle, a pair of fixed contact points respectively engageable by the movable contact points carried by said arms, means permanently electrically connecting said movable points on both arms with each other, and means electrically insulating said movable points from said fixed points when not engaged therewith.

2. A device of the class described comprising a pair of fixed contact elements, a rotatable spindle, a pair of arms loosely mounted to revolve independently about said spindle into and out of contact with said respective contact elements, means permanently electrically connecting said arms with each other, a pair of laterally projecting abutment members mounted on said spindle and angularly adjustable thereabout, each said abutment member being movable in its path to engage a respective arm and thereby to revolve the arm thus engaged about the axis of the spindle, and a finger-piece mounted on the end of said spindle.

3. A device of the class described comprising a disk of insulating material, a spindle extending loosely through said disk and coaxial therewith, a circular series of spaced metal elements set flush into each face of said disk symmetrically with respect to said spindle and insulated from one another, a pair

of conducting members swingable about said spindle as an axis in contact respectively with the series of elements in the faces of said disk, means permanently electrically connecting said members, means for connecting a pair of lead wires respectively to one element of each said series, and means including a lost motion connection between said spindle and each of said members for swinging said members independently around said spindle.

4. A device of the class described comprising a disk of insulating material having a central perforation, a metal element set flush in each face of said disk, said elements being insulated from each other by the material of the disk, a rotatable spindle extending through said perforation, a pair of electrically connected arms on opposite sides of said disk mounted to revolve loosely and independently about said spindle, each arm having a portion in constant contact with the adjacent face of said disk, said metal elements being in the path of contact of the respective arms, means projecting laterally from said spindle to engage and revolve said arms when the spindle is rotated, and means for connecting said metal elements into an electrical circuit.

5. A device of the class described comprising a disk of insulating material having a central aperture, a flanged metallic sleeve fitted in said aperture and projecting beyond both faces of the disk, a sleeve of insulating material fitted within said metallic sleeve, the ends of said insulating sleeve being substantially flush with the ends of said metallic sleeve, a metallic contact arm on each side of said disk, said arms being loosely mounted on the projecting portions of said metallic sleeve to swing about the axis thereof and to have permanent electrical contact therewith, each said arm having an inturned end bearing against a face of the disk, a contact point set flush in each face of the disk in the path of contact with the disk of the respective arm, perforated insulating washers against the ends of said sleeves, a spindle projecting through said washers and sleeves, a pair of collars adjustably fixed on said spindle and respectively adjacent to said washers, and means on said spindle for separately engaging said arms to rotate said arms respectively into contact with said contact points.

6. In a combination lock switch having a disk of insulating material, metal contact elements set into the opposite faces of said disk, a rotatable spindle extending through the center of said disk, and arms loosely revoluble about the axis of said spindle into and out of contact with said metal elements; a collar mounted on said spindle on each side of the disk, and set-screws in said collars adjustably securing said collars in place, said

set-screws having portions projecting from said collars to engage said arms when said spindle is rotated, whereby said arms may be revolved about said spindle.

In testimony whereof I have affixed my signature.

WILLIAM K. MASON.
